LAWRENCE S. SCHMIDT, OF PITTSBURGH, PENNSYLVANIA, ASSIGNOR TO SCHMIDT-McCORMICK COMPANY, OF PITTSBURGH, PENNSYLVANIA, A CORPORATION OF PENNSYLVANIA.

FURNACE-DOOR FRAME.

1,211,883.

Specification of Letters Patent.

Patented Jan. 9, 1917.

Application filed October 5, 1915. Serial No. 54,129.

To all whom it may concern:

Be it known that I, LAWRENCE S. SCHMIDT, a citizen of the United States, residing at Pittsburgh, in the county of Allegheny and State of Pennsylvania, have invented certain new and useful Improvements in Furnace-Door Frames, of which the following is a specification.

This invention relates to improvements in furnace door frames, and more particularly to hollow water cooled door frames formed from sheet metal.

The objects of my invention are to provide a door frame of this type which can be readily formed from sheet metal; which will practically avoid the difficulties heretofore presented relative to expansion and contraction of parts, and more particularly the tendency of the jambs, cheeks, or legs to be drawn together; in which the frame structure is formed in sections of a character which will enable the structure to be made more solid and substantial; in which the water circulation will be facilitated; and which can be readily cleansed when desired.

To these and other ends, my invention consists in the improved construction and combination of parts hereinafter fully described, illustrated, and particularly pointed out in the appended claims.

In the accompanying drawings, in which similar reference characters indicate similar parts in each of the views, Figure 1 is a front elevation of a frame constructed in accordance with my invention, parts being broken away to illustrate interior construction. Fig. 2 is a top plan view. Fig. 3 is a sectional view taken on line 3—3 of Fig. 1. Fig. 4 is a sectional view taken on line 4—4 of Fig. 1. Fig. 5 is a sectional view of a preferred form of wash-out valve.

The frame of my invention is preferably constructed in sections A and B, each complete in itself, the sections being substantially duplicates excepting that they have the "right and left" relation. Each section is formed of plates or sheets of metal and represents that part of the frame located on one side of a plane extending vertically through the center of the frame parallel to the frame side. For purposes of description, only one of the sections (A, for instance) is described in detail.

The inner face of the section is formed by a plate 10 which is flanged outwardly as at

10^a to form a side of the frame, the flanged portion having greater width than the depth of the water cooled portion of the section, the projecting portion, indicated at 10^b, being adapted to be secured to a buckstay of 60 the furnace (not shown). The plate 10 is also flanged as at 10^c, said latter flange following the general contour of the section with the exception of the side 10^a, and the top of the section which is closed by a separate plate. 65

The complementary plate of the section is indicated at 11, this plate being flanged, as at 11^a, in opposition to flange 10^c, the opposed edges of these flanges being united 70 together by welding through the length of contact of these edges. The plate 11 is also welded to flange 10^a, the plate being bent outwardly as at 11^b in order to increase the distance from front to rear of the section adjacent the flange 10^a. This enlarged portion extends from top to bottom of the section, the wall 11^b forming a guide for a vertically movable furnace door (not shown) which operates in connection with the frame. As 75 shown in Fig. 1, the section comprises a body or head portion a and the jamb, cheek or leg a'.

The top of the section is closed by a plate 12, which is preferably welded to plates 10 and 11 as indicated more particularly in Fig. 4; the top also extends over the enlarged portion heretofore referred to, see Fig. 2. As shown in Fig. 4, the top extends inwardly beyond the plane of plate 10, and 85 is then bent upwardly, as at 12^a, being provided with suitable bolt holes for a purpose presently described. The top preferably carries the inlet 13 and the outlet 14 for the water used in circulation, the section having 90 suitable water conducting pipes leading from the inlet for the purpose of producing any desired water circulation within the section, the out-flow of the water being through outlet 14. Obviously, the piping employed 100 may be varied to meet the conditions of service.

The jamb or cheek a' is provided with a wash-out valve 15, particularly shown in Fig. 5, said valve device being in the form 105 of a casing 15^a threaded to plate 11 and designed to project inwardly into the interior of the section, the casing having openings 15^b through its wall into the interior of the casing at a point intermediate its ends. The 110

casing is also threaded internally as at 15^c and 15^a. The threads 15^a are adapted to receive the threaded portion of a valve 16, while the threads 15^c are adapted to receive the threaded portion of an annular member 17 carrying a flange seat 17^a, the valve 16 having a face complementary to the seat. The valve 16 is also provided with a depression 16^a for the reception of a key (not shown).

10 The valve is assembled by first placing the valve 16 in position, after which member 17 is placed in position and the key inserted into the depression 16^a to rotate the valve so as to bring its face in contact with the seat 17^a. With the parts in this position (the position shown in Fig. 5) leakage of water from the interior of the section will be prevented. When it is desired to provide a wash-out action, only the key is inserted through the opening in member 17 into the depression 16^a and then turned to rotate the valve so as to cause the latter to recede from its contact with the seat, whereupon, the water and collected matter will 25 flow out through openings 15^b and the interior of member 17. This construction enables the frame to be washed out while the furnace is in operation, causing no delays or shut-downs. The particular advantage 30 of this form of wash-out valve lies in the fact that there is an entire absence of projecting parts liable to be damaged by striking with the tool, etc., and, in addition, the requirement of the use of a special key for 35 manipulating the valve, thus eliminating the possibility of accidental opening of the valve.

As shown in Fig. 1, the two sections have the "right and left" relation, thus placing the guides 11^b in position to perform their 40 functions with respect to the door. As shown in Figs. 1, 2 and 3, the head or body portions of the sections have sides opposed to each other, and I prefer, in securing the 45 frame in position, that these opposed sides of the sections be spaced slightly apart, thus permitting of the individual expansion and contraction of the sections without liability of distorting the frame, and especially without tending to cause the jambs or cheeks of the frame to be drawn toward each other, a difficulty which has heretofore been present in frames of this character. This 50 construction also does away with a cross connecting member and its accompanying disadvantages. In the present construction, by locating the lines of weld as shown, the effects of expansion and contraction on the 55 said welding lines of the sections is minimized; this effect is aided by the particular sectional formation of the frame which provides for the individual expansion and contraction of the sections. As pointed out, each section is preferably connected to a 60 buckstay, the part 10^b being preferably bolted 65

thereto. In addition, the sections are held fixedly relative to each other by the presence of a connecting member 18, preferably angular in cross section, and which is secured to the tops 12 and the flanged portions 12^a of each section, the member 18 having a length sufficient to enable it to be connected to both sections. The frame is connected to the furnace structure as is usual through the parts 12^a and 18.

What I claim is:

1. A furnace door frame formed of independent vertically separable sections, each section comprising sheet metal plates welded together and including a hollow jamb, a portion of the head or body, and a door guide, said sections having means adjacent the upper ends thereof for maintaining the sections in alinement.

2. A furnace door frame formed of independent vertically separable sections, each section comprising sheet metal plates welded together and including a hollow jamb, a portion of the head or body, and a door guide, each section having an independent water circulating means, and connecting means adjacent the tops of the sections for securing them together and maintaining the sections in alinement.

3. A furnace door frame comprising a pair of sections each of hollow sheet metal construction and comprising front, rear and top plates welded together, said sections each constituting a jamb and a portion of the head of the frame, each section having its front and rear plate flanged and disposed with the edges of the flanges abutting and welded together, said flanges combinedly forming spaced welded walls in the head of the frame, the weld line of each of said walls being approximately equi-distant from the outer faces of the front and rear plates.

4. A furnace door frame comprising a pair of sections each of hollow sheet metal construction and comprising front, rear and top plates welded together, said sections each constituting a jamb and a portion of the head of the frame, each section having its front and rear plate flanged and disposed with the edges of the flanges abutting and welded together, said flanges combinedly forming spaced welded walls in the head of the frame, the weld line of each of said walls being approximately equi-distant from the outer faces of the front and rear plates, and connecting means adjacent the tops of the sections for securing them together and maintaining the sections in alinement.

5. A furnace door frame comprising a hollow sheet metal structure having a head and depending jambs, the head portion being formed in two independent sections, each section having a top welded thereto, each top having a projecting flanged portion, and a member for securing said pro-

jecting flanged portions together in substantially longitudinal alinement.

6. A furnace door frame comprising a hollow sheet metal structure having a head and depending jambs, the head portion being formed in two independent sections, each section having a top welded thereto, each top having a projecting flanged portion, and a member for securing said projecting flanged portions together in substantially longitudinal alinement, said member being angular in cross section.

7. A furnace door frame comprising a hollow sheet metal structure having a head and depending jambs, the head portion being formed in two independent sections, each section having individual water circulating means, and an individual controllable drainage member for each section, said

drainage member being located wholly within the plane of the section.

8. A furnace door frame comprising a hollow sheet metal structure having a head and depending jambs, the head portion being formed in two independent sections, each section having individual water circulating means, and an individual controllable drainage member for each section, said drainage member including a casing, and removable valve and valve seat members carried by the casing.

In testimony whereof I affix my signature in presence of two witnesses.

LAWRENCE S. SCHMIDT.
